22 Claims. (Cl. 66—49)

This invention relates to a method of circular knitting of partially reinforced seamless hose goods, particularly of fine hose with reinforced heel and toe, and perhaps reinforced sole, as well as the circular knitting machine serving to carry out this method.

This is a continuation-in-part of my co-pending United States patent application, Serial No. 852,915, filed November 13, 1959, now abandoned.

A production method of heel- and toe-reinforcement with endless reinforcement thread by the so-called reciprocatory movements is well known. In this manner of operation the circular knitting machine executes a reciprocatory movement corresponding to the width of the reinforced part, which involves a decrease of the working speed as well as a constant reversal of the direction of movement of the cam ring in machines with stationary cylinder, or of the cylinder in machines with revolving cylinder. In such cases the revolving cam ring or cylinder at its reversal position in each case must be braked to a standstill and then in the opposite direction again be accelerated to its working speed. This involves a great degree of pulsation in the power requirement of the machine as well as a decrease of the production because of the periodically decreased working speed.

In order to overcome these disadvantages, it has been proposed, to avoid the reciprocatory movements and to waste in knitting the reinforcement thread by revolving the cam system or cylinder constantly in one direction so that the reinforcement thread floats in the unreinforced part and hereupon is later cut off at the reinforcement edges (compare U.S. Patent 2,709,353 and British Patent 756,941). This cutting off of the floated reinforcement threads requires an additional operation besides additional cutting devices, and means a material loss. Additionally, the cutting off of the floated reinforcement threads has as consequence short thread ends, which push-through from inside to the surface of the goods or, in the case of long thread ends, are visible through the fine knitted material.

The purpose of the invention is accordingly to circularly knit a seamless hose, if possible in the quality of a cotton hose, by means of latch needles or point needles, with endless reinforcement thread and to avoid the disadvantages of the hitherto known processes.

This objective is accomplished in accordance with the invention in the following manner:

The base thread as well as the reinforcement thread are first of all jointly knitted. Beginning at the end-margin of the reinforcement, the base thread is then alone knitted further, while the reinforcement thread is knitted back alone to the starting margin of the reinforcement, from where subsequently it forms a course with the base thread, so that in the reinforced part one course formed of base thread and reinforcement thread alternates with a course of the reinforcement thread alone. For this, two cam systems, one for the base thread and reinforcement thread, the other for the reinforcement thread only, operate with reference to the cylinder relative movements in opposite direction to one another, under constant maintenance of their direction of rotation

2

and speed. In doing so it is immaterial whether the cylinder stands still or rotates. In machines with a stationary cylinder, the cam system for the base thread and reinforcement thread runs constantly and with constant speed in the one direction and the cam system for the reinforcement thread runs constantly and with the same speed in the opposite direction around the cylinder. In machines with revolving cylinder, the cam system for the base thread and reinforcement thread is stationary,

- 5 whereas the cam system for the reinforcement thread revolves constantly and with constant speed, which corresponds to at least double the cylinder speed or a higher multiple of the cylinder speed, rotating in the same direction of rotation as the cylinder.
- 10 The new process offers the following advantages in comparison to the hitherto known ones:

The reinforcement thread is knitted without reciprocatory movements, and so, without reversal of the revolving cylinder or cam ring, at constant working speed.

20 Cutting-off floated threads at the margins of the reinforcement part is eliminated. By endless knitting in of the reinforcement thread the further advantage is obtained as compared with hitherto known reciprocatory movements: Since in the reinforcement part alternates always 25 one course knitted from the base thread and the reinforcement thread with one course knitted only from the reinforcement thread, and therefore in the reinforced part twice as many courses are knitted as in the unreinforced part, the reinforced hose part becomes longer

30 than the unreinforced part. Thus, heel and toe, perhaps also the sole, take on, while knitting at undiminished speed, a form which in previous circular knitting processes could only be obtained either after the knitting through stretching of the reinforced meshes in the sole

35 part and shrinking of the meshes in the upper-foot-part by forming and plasticizing, or, during the knitting, through development of the heel by the retarded reciprocatory movements above referred to. In the previous customary forming process, in hose without wedge-heel

40 the stitch pattern was distorted and warped. In the new process, the less elastic reinforced meshes are not stretched, but merely a slight shaping-out, without much strain of individual mesh rows, suffices.

- In the U.S. Patent 2,740,277 is described a circular knitting machine for the carrying out of a wrap-stitch knitting method, in which the wrap-yarn first knitted in the same direction as the base thread, is alone knitted-back by means of an auxiliary cam system revolving in opposite direction to the normal cam system, in order 45 to produce through intermediary rows arched surfaces. However, with this described system only about 100 needles, thus a comparatively small region, may in each case be supplied by the wrap-yarn guide, which is arranged in the nature of crank over the needles and carries out
- 50 a movement completely independent of the revolving normal—or also auxiliary—cam-system.

The process in accordance with this invention and the circular knitting machine for the carrying out of this process differs from this known device in that a tubular article is produced for the production of a seamless hose, 60 in which a reinforcement thread is, as distinguished from the known wrap-stitch knitting method, used up in knitting over approximately one half or more of the cylinder circumference. The reinforcement thread guide revolves with a second revolving cam system, during the knitting of the course formed alone from the reinforcement thread, over the region of the reinforcement section.

Thus, it is possible to knit a seamless hose in continuous rotation, but simultaneously to give this hose a partial shaping in the foot part and to avoid the cutting-off of the reinforcement thread at the margins of the reinforcement, without it being necessary to cut apart and sew

the hose after completed knitting, as is described in the process of U.S. Patent 2,740,277.

Further details of the process in accordance with the invention and the circular knitting machines for carrying it out, are described in connection with the drawings.

In the drawings are:

FIG. 1, a schematic representation of the total arrangement in perspective lateral view;

FIGS. 2 and 3 are schematic representations of the successive movements between cam systems and cylinders, in top view;

FIG. 4 is a side elevation of a hose with reinforced foot as produced by the invention;

FIG. 5 is a schematic representation of the build-up of the base—and reinforcement—rows;

FIG. 6 shows as a form of circular knitting machine constructed in accordance with the invention, in longitudinal section;

FIGS. 7, 7a and 7b show in a developed view of the cam systems and of the needle rim seen from the inside, the various working phases of the process in accordance with the invention;

FIGS. 8 and 9 are pictures of meshes, which show the linkage in the reinforced part;

FIG. 10 shows in perspective a detail from FIG. 6 the arrangement of the thread guide for the reinforcement thread;

FIGS. 11 and 12 show the manner of working of the sinker cam in conformity with the FIGS. 7a and 7;

FIG. 13 shows the sinker cam in cut-out in its position during the knitting of the unreinforced hose parts;

FIG. 14 shows in longitudinal section the upper part of a circular knitting machine as in FIG. 6, however in modified form;

FIG. 15 shows in vertical section the revolving cam system for the reinforcement thread in enlarged representation;

FIG. 16 is a schematic plan view of the sinker cam during the disengaging of the revolving sinker cam in accordance with the embodiment of FIG. 14;

FIG. 17 is an enlarged representation from FIG. 16 with (disengaged) sinker cam for the reinforcement thread;

FIG. 18 shows a similar representation as in FIG. 16, however during the reengagement of the revolving sinker cam for the reinforcement thread;

FIG. 19 shows an enlarged fragmentary perspective view of the apparatus of FIG. 18;

FIG. 20 shows in perspective the control device for the switching-off and switching-on of the revolving sinker cam;

FIG. 21 shows in section the drive of the thread guide for the reinforcement thread in enlarged representation in accordance with FIG. 14;

FIG. 22 shows the device in vertical section positioned above the cylinder and the dial disc, for the supply of the reinforcement thread to the periodically revolving reinforcement guide;

FIG. 23 (which is on the sheet bearing FIG. 7) is a side view of a needle and its actuating jack;

FIG. 24 (which is on the sheet bearing FIG. 7a) is a side view of a form of needle with a pair of butts, and an actuating jack with numerous butts; and

FIG. 25 (which is on the sheet bearing FIG. 7b) is a side view of a needle and its actuating jack.

Referring first to FIGS. 1, 3, 6 and 7, there is shown a circular knitting machine with rotating needle cylinder, individually actuated latch needles, dial disc, sinkers and transfer jacks.

In FIG. 1 is shown the needle-cylinder Z of the circular knitting machine in accordance with the invention schematically with the arrangement and movement of the cam systems I and II. The cylinder Z is adapted to revolve at uniform speed in the direction of the arrow P. In longitudinal grooves 2' of the cylinder Z are slidably

seated the latch needles 2 which obtain their knitting movement by needle butts 3' and 3" through the two cam systems I and II respectively positioned at levels one above the other. The upper cam system I is stationary.

5 The lower cam system II is positioned on a cam ring revolving around the cylinder. The stationary cam system I operates needles 2 by the needle butts 3' and serves for the knitting of the base thread G in the direction of the arrow P₁ over the entire cylinder-circumference and, in addition, serves for the knitting of the reinforcement thread S in the direction of the arrow P₁ over the sector A-B of needle-cylinder Z, which corresponds to the maximal width of the reinforced hose part in the heel, sole or toe. It should be noted that at only those needles lying in sector A-B are both butts 3' and 3". The remaining needles have only butts 3'. Cam system II revolves in the direction of turning P of the cylinder Z with uniform speed which may be designated v_{II}, wherein this corresponds to at least the double or a multiple of cylinder speed v_z. Cam system II operates only those needles 2 which have needle butts 3". These needles which have butts 3' and butts 3", are positioned over the sector A-B of the needle-cylinder Z for the knitting of the reinforced hose-part.

20 The movement of the cylinder Z and of the revolving cam system II with respect to the stationary cam system I (whose velocity v_I=0) is represented in FIG. 3 schematically in top view. There is indicated for the cylinder Z a speed v_z, the cam system I the speed v_I=0, i.e., the cam system I is stationary, and the cam system II the speed v_{II}=2v_z or also 3v_z, 4v_z.

25 The base thread guide G', assigned to the stationary cam system I, is likewise stationary and rigidly connected with the cam system I. The reinforcement thread guide S', assigned to the cam system II, works as trailing thread guide alternately together with the cam system I and the cam system II. Thus, base thread G (FIG. 1) and reinforcement thread S are first jointly knitted from A to B in the direction P₁. During this operation the reinforced thread guide S' is stationed in a fixed position adjacent the base thread guide G'. At the end margin B of the reinforcement, the reinforcement-thread remains at the margin needle; and, for a moment, reinforced thread is drawn from its spool (FIG. 22) without any knitting thereof. This drawing out without knitting continues only until the cam system II overtakes the reinforcement thread guide, whereupon, as is later described in detail, the reinforcement thread guide is released from its fixed position and moves with the cam system II. During this last-mentioned movement the course of reinforcement thread 30 alone is knit. Thus, while the base thread G is alone knitted by means of the cam system I in the unreinforced hose part corresponding to the remaining cylinder-circumference from B to A in the direction P₁, the reinforcement-thread alone is worked-back by means of the cam system II in the opposite direction (arrow P) to the starting margin A of the reinforcement. Then from point A is again knitted by cam system I a course consisting of a base- and a reinforcement-thread in the direction P₁ to 35 B. Through repetition of these operations is knitted in the reinforced part one row each of base- and reinforcement-thread alternating with a row which only consists of the reinforcement thread, as shown in FIGS. 4 and 5. On the other hand, in the unreinforced hose part the base-thread alone is knitted.

40 Similar mesh goods are described in U.S. Patent 2,707,381, in which are formed, with wrap-yarn knitted in specific sections of the goods to additional rows, enlargements cup like or loop-like. By that method, because of the working manner of the circular knitting machine such as is also described in U.S. Patent 2,740,277, the wrap-yarn can be knitted only within the range of the wrap yarn guide avertence, so that the bulging goods surfaces are composed of several sections. In seamless

fine hose visible seamed places between the individual part ranges are, however, very disturbing and therefore inadmissible. Besides, through the wrap yarn are only knitted additional part-rows, so that the hose would not undergo any reinforcement. Therefore, in accordance with the invention, there are formed over the entire range of the reinforcement part a joint row of base- and reinforcement-thread and subsequently a row only of the reinforcement-thread, in which the reinforcement-thread alone is knitted back from the end-margin of the reinforcement to the starting margin.

The FIGS. 4 and 5 show schematically the formation row by row of a hose and of a tube in which the base thread G was continuously knitted over the entire cylinder-circumference, while the reinforcement part of the reinforcement thread S forms in each case one row together with the base thread and an intermediary row alone without the base thread.

THE FIGS. 8 and 9 show illustrations of the meshes in the reinforced and unreinforced hose part. The courses formed only from the base-thread G, because of the level schematic drawing, are twice as large as the courses formed from the reinforcement-thread S. Actually, in the hose the courses are all equally large, so that a bulge in the reinforced part is attained, since here in this area twice as many courses as in the not-reinforced hose-part were knitted.

FIG. 8 shows the partial binding-in of the reinforcement-thread at the margin of the reinforcement, FIG. 9 the complete binding-in of the same, as is hitherto possible only on a full-fashioned hosiery machine (straight-bar knitting machine).

For the process in accordance with the invention it is immaterial whether the cylinder revolves, as described on the basis of FIG. 1 and 3, or whether it is stationary as shown in the illustration of movement according to FIG. 2, and both cam systems I and II revolve in a direction opposed to each other with equal and constant speed. To the cylinder Z, then is assigned the cylinder speed $v_z=0$, to the cam system I the speed v_I , and to the cam system II the speed $v_{II}=-v_I$ (or $-2v_I$; $-3v_I$ . . . $-nv_I$).

In the following is described an embodiment of the invention on the basis of a circular knitting machine with (rotating) needle-cylinder, individually moved latch needles, sinkers and transfer jacks in the dial disc as well as pattern jacks for the selection of the needles, in which the cam system I is stationarily positioned while the cam system II revolves with double the cylinder-speed ($v_{II}=2v_z$).

FIG. 6 shows the upper part of such a circular knitting machine in accordance with the invention, which is positioned on a machine frame of known construction, not shown in the drawings and not part of the invention and therefore not described here in detail.

The needle-cylinder Z is mounted on a further cylinder Z_4 revolving with it, provided with jacks 4. The inner-sleeve 5 of the cylinder Z_4 is driven by the cone-wheel-rim 6. Spur-wheel rim 6' is integral with the cone wheel and drives the spur-wheel 7. Coupling 80 is connected to the spur-wheel 7 through a conventional clutch arrangement and is also connected to shaft 8 so as to impart rotation thereto when the clutch arrangement is in the engaged condition. Means, not shown, are provided to provide the clutch arrangement is engaged condition when knitting reinforcement and is in disengaged condition when knitting a length of hose without reinforcement. The shaft 8 passes through the frame 13 and is journaled in the sleeve of the spur-wheel 7. The shaft 8 drives, by gear 9, the ring 90 carrying the revolving cam system II, further by the wheel 10 and the toothed rim 100, the revolving sinker cam 16, as well as the gear 11, the ring gear 110 together with the reinforcement thread guide S' positioned on it. The cam system I as well as the base-thread-guide G' are stationarily positioned on the frame

13. Of the needles 2 positioned at the periphery of the cylinder Z and revolving with it, those concerned with the working-out of the reinforcement, have at least a further needle-butt 3''. The needle-butt 3' works together with 5 the cam system I and the needle-butt 3'' with the cam system II. Likewise, the sinkers 14 have one butt 14' for the actuation of the base-row and a further butt 14'' for the actuation of the course formed by the reinforcement-thread alone by means of the sinker cam 16 synchronously revolving with the cam system II. The other sinker cam 17 works together with the cam system I and 10 therefore is likewise stationarily connected with the frame 13. All revolving parts are jointly driven by the bevel gear 6 and the shaft 8, as described above. By the suitable 15 selection of a transmission gear ratio 1:2 the sinker cam 16 revolve together with the cam system II and the reinforcement thread guide S with double the cylinder speed.

FIG. 10 represents a detail from FIG. 6 in perspective view. On the ring gear 110, driven by shaft 8 and the gear 11, is mounted a ring 111, on which is slidably positioned the reinforcement-thread-guide S', for example developed as trailing-thread-guide. A spring 20 presses the thread guide S' against the ring 111, so that a dragging of the thread-guide S' takes place through the revolving gear 110 via the ring 111. By means of the buffer 21, positioned on the frame 13 together with the cam system I independent of the ring 111, which buffer may be connected and disconnected by pivotable bar 22, the reinforcement-thread-guide S' is held back at the cam system I, and slides on the ring 111 which turns constantly with the speed of the cam system II.

Referring again to FIG. 6, means are provided for selecting the needles to participate in knitting of the reinforced section. The lower cylinder Z_4 is provided with 35 jacks 4 mounted on the cylinder Z_4 as the needles 2 are mounted on the cylinder Z. The jacks 4 cooperate with the needles 2, in a manner generally known in the art, to facilitate the knitting operation, and in addition perform further function as is shortly to be described.

40 The manner in which the above-described parts operate will be better understood from consideration of FIGS. 7, 7a, and 7b. As noted above, these figures are developments of the cylindrical parts of the knitting machine corresponding, respectively, to various steps of the operation. In each case, the development is viewed from within the cylinders Z and Z_4 .

In these figures, from top to bottom, there is indicated the section A-B, the reinforcing thread S and base thread G, the position of the hooks of the needles 2, the direction of rotation of the cylinder (arrow P), the needle butts 3', the stationary cam system I which cooperates with the needle butts 3', the needle butts 3'', and the cam system II which moves in the direction of the cylinder with twice the speed of the cylinder and which cooperates with 55 the needle butts 3''. These parts are mounted on or cooperate with parts mounted on the cylinder Z. Also shown in the developments, is the cylinder Z_4 and parts associated therewith. As noted above, mounted on the cylinder Z_4 , are the jacks 4. These jacks are provided 60 with jack butts according to the position of the jacks on the cylinder Z_4 . All of the jacks have jack butts 41 and 42 (see FIG. 7 and the figure at the right thereof, namely, FIG. 23) and these jack butts are for control of the knitting when reinforcement thread is not knit into the 65 fabric. The jacks in the section A-B are provided with jack butts 4' for controlling the knitting of reinforcement thread. The jack butts 4' include jack butts 401-414, and these are distributed so as to provide for the knitting of the reinforcing thread to various fractions of the circumference of the knit article.

70 For cooperation with the jack butts 41, and 42, jack cams are provided, and for cooperation with the jack butts 401-414, jack slides are provided. The jack cams and jack slides are stationary. First there are the jack cams e and e' for actuating the butts 42, and the draw-off

cams *c* and *c'* for actuating the butts 41. The jack cam *e* and draw-off cam *c* cooperate with the operation at cam station I. Also cooperating with this operation (when reinforcement thread is being knit-in) are the selector means in the form of jack slides *M*₁. The jack slides *M*₁ include the individual slides *m*₁–*m*₁₄ and are at a fixed location adjacent the cylinder *Z*₄, while at the same time being movable into and out of the operative position wherein they are set to engage the jack cams 401–414. Jack slides of the group *M*₁ are placed in operative position when the reinforcement thread is to be knit. More particularly, the jack slides *M*₁ are for cooperation with the jack butts 401–414 to provide the knitting of the base thread and the reinforcing thread in a single course. Operation of the jack slides *M*₁ is further described below.

Also in the part of FIGS. 7, 7a, and 7b corresponding to the cylinder *Z*₄, there are shown jack slides for cooperation with the cam system II. These jack slides include the jack slide *e'* and draw-off slide *c'*, and the jack slides *M*₂. The operation of the jack slides corresponds with the operation of jack slides *e*, *c* and *M*₁, and slides *M*₂, like slides *M*₁, are at a fixed position about the circumference of the cylinder *Z* and are movable into and out of an operative position wherein they are disposed for engagement by the jack butts 401–414.

At the condition shown in FIG. 7, a course of reinforcing thread is being knit at cam station II, while at cam station I, the base thread alone is being knit. In the position of FIG. 7, the jack butts 4' are idle (as will be better understood from the ensuing description), and the symmetrical array of these butts can be seen. Such an array provides a symmetrical decrease and increase of reinforcement thread width or circumferential disposition, as will be later better understood.

In FIG. 7a, the cylinder section A–B is passing the jack cams *e* and *c* and the jack slides *M*₁ and base thread and reinforcement thread are being knit into a single course.

In FIG. 7b, the jack butts 41 and 42 are passing the jack cams *e'* and *c'*, and 401–414 are passing the jack slides *M*₂ and the needles 2 are being set by these elements for the action of the cam station II which will occur upon the said cam station overtaking the needles so set. This overtaking has occurred at the condition shown in FIG. 7.

The production of a seamless hose in accordance with the process of the invention takes place in the following manner:

First the welt is knitted with the aid of the dial disc and the transfer jacks in the usual manner and transferred and subsequently the hose-length worked. For this may also be used several cam systems I with a corresponding number of base thread feeds *G*, so that in each cylinder rotation several courses are formed. During this time the shaft 8 is, through the coupling 80, separated from the gear 7, so that the cam system II, the sinker cam 16 and the reinforcement-thread-guide S' are in inoperative position. For this purpose the sinker cam 16, according to FIGS. 11, 12 and 13, is radially displaceable positioned on the slide 161 and occupies during the knitting of the hose-length the position shown in FIG. 13. Then the sinker butts 14" travel behind the sinker cam 16, without being engaged by it. The sinkers 14 may then unhindered follow the radial movement imparted by the stationary sinker cam 17.

The slide 161 is operated through a customary cam means, for example through a steering cam 163, as it is schematically indicated in FIG. 13, or through a roller or the like, mounted on pin 162. In like manner as the sinker cam 16, the cam system II stands still and is withdrawn from the path of the needle butts 3". This device for the withdrawal of the cam system II is not shown in detail in FIG. 6. It may be a known device, as for example later described in the modification of the invention

in FIG. 15. The reinforcement thread guide S is stopped through the buffer 21 (FIG. 10).

At the start of the knitting of the reinforced foot-parts of the hose, only one cam system I can be in operation. The coupling 80 is then engaged to rotate shaft 8, the sinker cam 16 drawn-back and the cam system II advanced into the path of the needle-butts 3", so that the knitting process in accordance with the invention may be carried out.

Referring to FIG. 7, and in particular to the action at the cam station II, the jack butts 42 engage the jack cams *e* whereupon the needles 2 are raised to just below the level *a* where the needle butts 3' are at a level for actuation by the cam *f* of cam station I. The needle butts 3' pass through the cam station I to cast-off *b* and knitting in the usual manner and without reinforcement is performed. The jack slides *M*₁ do not operate, as the jacks 4 at the section of the cylinder under consideration have no jack butts for cooperation with the slides *M*₁. The jack cam *e* and draw-off *c*, however, cooperate respectively with the jack butts 42 and 41 to provide the needles 2 in position for the knitting at cam station I.

The start of the knitting of the reinforced foot-parts in the hose is indicated in FIG. 7a. The cam system II is switched-on and revolves with double the cylinder speed. Since it is just outside of the *AB* Sector of the needle-cylinder *Z*, where the needles 2 have no butts 3", the cam system II revolves freely at first, until it has overtaken the needles 2 with butts 3" revolving with the cylinder *Z* (FIG. 7). During rotation of the cam system II along the cylinder *Z* outside of sector *AB*, the thread-guide for the reinforcement-thread S is held stationary by the buffer 21 (FIG. 10), beside the thread-guide for the base-thread *G*, as shown in FIG. 7a. Base-thread *G* and reinforcement-thread S now knit with the stationary cam system I the course which is formed jointly by the base-thread and reinforcement-thread. Through the jack butt 42 of the jacks 4 positioned under the needles in the cylinder *Z*, and the cam *f*, all needles 2 are lifted so high that they grasp the base-thread *G* and subsequently pass through the cam system I. The jacks 4 positioned in the cylinder-sector *AB* for the knitting of the reinforced hose parts have additional jack butts 401–414 which in each case cooperate with the jack slides *M*₁ to simultaneously knit the reinforcing threads.

The jack slides *M*₁, as noted above, are at a stationary position with respect to the circumference of the cylinder and are movable between a butt engaging position and an inoperative or retracted position. The jack slides *M*₁, which includes the jack slides *m*₁–*m*₁₄, can be provided so that they are individually selectively movable into and out of the retracted position in suitable time sequence with respect to cylinder rotation to cooperate with the jack butts 401–414 to provide a desired pattern for the reinforcement thread. As is discussed hereinafter, the operation of the jack slides as just described can be provided by means known in the art.

To facilitate understanding of the operation, jack slides in the operative position are shown in full lines, whereas jack slides in the retracted or inoperative position are shown in dashed lines. Thus, in FIG. 7a, of the jack slides *M*₁, the slide *m*₁ is in the operative position and slides *m*₂–*m*₁₄ are in the inoperative position. For this condition, jacks 4 having jack butts 401 (and it will be observed that only some of the jacks 4 have jack butts 401) are raised by response to cooperation of the jack butt 401 and the slide *m*₁ to a level higher than that corresponding to the cooperation of the jack butts 42 and cam *e*, namely so that the needles 2 responding to such action are raised to above the level *a*. By reason of this raising of the needles 2, the needles grasp not only the base thread *G* but the reinforcement thread S as well. At this phase of the operation, the reinforcement thread guide S' is stationary just behind the base thread guide *G'* and hence the reinforcement thread is available for the knit-

ting. The knitting operation at station I is then performed in the usual manner, but the course section being knit includes the two threads.

In FIG. 7b the needles 2, selected for the reinforcement, have just finished the course formed by the base- and reinforcement-thread. The reinforcement-thread-guide S' remains for a time at the cam system I, until it is overtaken by the cam system II at which time it moves on with the cam station II. Since only the jack slide m_1 is in operative position, the needles 2 whose jacks do not possess any jack butt 401, are not brought to above the level a , and therefore cannot catch the reinforcement-thread S, so that now at station I, only the base thread is being knit.

After the needles 2 in the cam system I have passed through the cast-off position b , they pass through a station where there is positioned jack cam e' , draw-off cam c' and the jack slides M_2 . At this station, the needles 2 are positioned for the course, which is formed by the reinforcement-thread alone by means of the revolving cam system II. The operation of the jack slides, etc. at the station including slides M_2 , is similar to that occurring at the station including slides M_1 . The needles selected are brought to a level a' and remain there, until they are withdrawn by the cam system II (FIG. 7), which acts on the butts 3" of the needles 2, overtaking the cylinder in the sector $\overline{AB}$.

The operations indicated in FIG. 7 fit in with those shown in FIG. 7b.

The cylinder-sector $\overline{AB}$, in whose range the reinforcement is worked, has passed the stationary cam system I and also stationary jack-slides M_1 and M_2 . Now at the cam system I the base-thread alone is knitted. The cam system II revolving with double the speed of the cylinder has overtaken the butts 3" of the needles 2 and in passing the cam system I has taken with it the reinforcement thread guide S' (FIG. 7). At the moment the cam system II passes the stationary cam system I, the buffer 21 (FIG. 10) is drawn-back for a short span of time through the pivoted lever 22, so that the thread-guide for the reinforcement thread S, sliding up to now on the turning ring 111, is gripped by the pressure of the spring 20 and revolves with the cam system II.

The buffer 21 is immediately again swung into its original position as shown in FIG. 10, so that the thread-guide for the reinforcement-thread S is again stopped against the buffer 21 after one revolution, while the cam system II revolves alone with constant speed v_{II} . The needles which have not been brought into the clearing position a' (to above the level a') by means of the jack slides M_2 are withdrawn by the slope d of the cam 98 (at cam system II), before they can pick up the reinforcement-thread S. The selected needles 2 in the clearing position a' catch the reinforcement-thread S and knit it in the cam system II to the course formed by the reinforcement thread. Thereupon the operation cycle repeats, as described in connection with FIG. 7a, in order to knit further courses with partial reinforcement. According to which of the jack slides m_1-m_{14} and which of the jack slides $m'_1-m'_{14}$ is actuated, the width of the reinforcement is varied.

The actuation of the selector cams or jack slides M_1 and M_2 takes place through a generally known pattern switching device, such as is shown for example in the U.S. Patents 2,208,698 or 2,146,647 for a similar purpose. This switching device is not the subject of the invention and is therefore not more completely described.

FIG. 11 and FIG. 12 show in connection with FIG. 6 the sinker cams 16 and 17 as well as the positioning of the sinkers 14 with the sinker butts 14' and 14" in schematic plan view. From these figures may also be seen the position in each case of the sinker cam 16 revolving with the cam system II, with reference to the stationary sinker cam 17 which acts together with the stationary cam system

I, during the working phases of the process in accordance with the invention shown in FIGS. 7 and 7a.

The sinkers in the sector $\overline{AB}$ have additional butts 14", which correspond to the needle butts 3" and are operated by the revolving sinker cam 16 in knitting the courses formed alone by the reinforcement thread. All sinkers over the entire cylinder-circumference have butts 14', which correspond to the needle butts 3' and are operated through the stationary sinker cam 17. The position of the sinkers in FIG. 11 corresponds to the needle position in FIG. 7a, likewise FIG. 12 corresponds to the FIG. 7, wherein the cam system I together with the sinker cam 17 is stationarily positioned, while the cam system II together with the sinker cam 16 revolves at double the speed of the cylinder and of the sector $\overline{AB}$. The sinker cam 16 is radially displaceably seated in accordance with FIGS. 11 and 12 on a slide 161, in order to be able to stop the sinker cam 16 during the knitting of the hose length, as well as to stop the cam system II, as shown in FIG. 13.

At the start of the knitting of the reinforced hose part, as described in FIG. 7a, the sinker cam 16 occupies the position shown in FIG. 11, i.e., it revolves just as the cam system II with the speed v_{II} , without operating the sinkers 14, until after the first revolution it has overtaken the sinkers 14 with butts 14" revolving with the cylinder Z with the speed $v_z = \frac{1}{2} v_{II}$.

In FIG. 12 is shown the operation in accordance with FIG. 7, the sinker cam 17 works together with the stationary cam system I, where now the base thread alone is being knitted, while the sinker cam 16 revolving and acting together with the cam system II, participates in the knitting of the reinforcement thread S in the course started by the reinforcement thread.

After finish of the knitting of the reinforced hose parts, the coupling 80 (FIG. 6) is again disengaged, so that the revolving parts are stopped and the cam system II as well as the sinker cam 16 inactivated, as this takes place during the production of the hose-length and the welt and has already been described above.

At a speed of revolution of the cam system for the reinforcement thread, which corresponds to double the cylinder rotating speed, with the device described may be extended the width of the reinforced part in the maximum case over half the cylinder circumference. This is only theoretically possible, since at the meeting of the cam system II for the reinforcement thread with the cam system I for the base—and reinforcement—thread, the cam systems can never simultaneously act upon the same needles, in order to prevent a damage to the needles and knitting defects. Thus, the possible length of the cylinder-sector $\overline{AB}$ in which the reinforcement may be worked, may be calculated from the following relationship: Maximal reinforcement width:

55 $\overline{AB} = \text{cylinder-circumference times}$

$$\frac{v_z}{v_{II}} \text{ minus width of cam system}$$

$v_z = \text{cylinder rotation speed}$

60 $v_{II} = \text{speed of revolution of the cam system II}$

From this it is evident that upon increase of the cam system revolution speed the reinforcement width decreases, thus, for example, at triple revolution speed ($v_{II}=3v_z$) it amounts to less than one-third of the cylinder circumference. Since, however, the necessary cam system width requires a considerable portion of the cylinder circumference in small cylinder diameters, as they are used in hose circular knitting-machines, the reinforcement width obtained with the device described does not always suffice.

In accordance with a further characteristic of the invention an essential improvement of the previously described process in accordance with the invention can be obtained in which for the obtaining of a still greater reinforcement width the cam system II revolves for the reinforce-

ment thread with the multiple cylinder-rotation-speed v_z , and with the same direction of rotation as the cylinder Z, and periodically is switched on only during one of these revolutions per cylinder-rotation for the knitting backwards of the reinforcement thread alone, wherein the cam system I for the base- and reinforcement-thread is arranged stationary.

To carry out this changed operation used is made of a coupling capable of being switched on and off, for the periodic pick up of the thread-guide for the reinforcement-thread. Additionally is provided a cam-ring with sloping surfaces at its underside, which is mounted on a second ring, positioned stationary and coaxially with the cylinder and provided with corresponding sloping surfaces on its upper side, so that the first mentioned cam-ring is operable in a small angle and displaceably positioned coaxially to the cylinder, for the operation of the revolving cam system II for the reinforcement thread. Another similar pair of cam-rings serves for the operation of the coupling for the pick up of the thread-guide for the reinforcement-thread. The sinker cam revolving with the cam system II for the reinforcement-thread is actuated by a stationary ring coaxial with the cylinder, which has two steering-latches pivotable in and out, independently of one another. Thus the cam system II revolves with multiple cylinder-rotation-speed, actually a repeated meeting of the two cam systems I and II takes place for each cylinder rotation, but since the revolving cam system II is always connected only during one revolution per cylinder-rotation, in each case is to be considered for the insertion of the needles for knitting the reinforced part, only one meeting, in which the needles for knitting the reinforced part may not be operated simultaneously through both cam systems I and II. In accordance with the changed operation then results the following relationship between the speed of revolution v_{II} of the cam system II for the reinforcement thread, the cylinder-rotation speed v_z and the maximum reinforcement width $\overline{AB}$:

$AB = \text{cylinder circumference times}$

$$\left(1 - \frac{v_z}{v_{II}}\right) \text{ minus cam system width}$$

From this it is evident that upon increase of the cam system revolution speed v_{II} the reinforcement width may be increased and, for example, with four-fold cam system revolution speed as against the cylinder-speed ($v_{II}=4v_z$) the reinforcement-width $\overline{AB}$ may be increased up to three-quarters of the cylinder-circumference minus the cam system width. However, in practice it has proved favorable to let the cam system II for the reinforcement thread rotate with the three times the cylinder rotation speed ($v_{II}=3v_z$). Therefore, in the following is described in detail an example of operation with three times cylinder-rotation-speed of the cam system II for the reinforcement thread on the basis of FIGS. 14 to 21.

In FIG. 14 is shown in section the complete arrangement of the upper part of a circular knitting machine, namely in the form changed as compared with that described in FIG. 6.

The cylinder is composed, as already described in FIG. 6, of the needle cylinder Z for the needles 2 and a sub-cylinder Z_4 for the jacks 4 and is mounted on the shaft 5 of the bevel gear 6, by which it is driven. The gear 6 has a spur gear rim 6' which engages with the gear 7 to drive shaft 8. The gear 7 is rotatable on the shaft 8 with a sleeve 31 and is coupled to the shaft 8 by a coupling clutch 30. However, the shaft 8 is driven, in this instance, with a gear ratio 1:3, and carries at its upper part the gear 9 to drive the revolving cam system II for the reinforcement thread by the ring gear 90; also a gear 19, which engages a ring gear 100 for rotating sinker cam 16 for the reinforcement thread; and another gear 11, which drives, by a ring gear 110 a clutch 27, 28 for engagement with reinforcement thread guide S. The ma-

chine frame has a machine table 13, and a base 131, and a cylinder 134, while on the base 131 is mounted an upper frame 132 to receive the machine-head upper part and a ring cam 133 with the stationary cam system I for the base and reinforcement thread.

FIG. 15 shows in broken section the revolving cam system II for the reinforcement thread. The ring gear 90 is, as may be seen in FIG. 14, seated in the lower carrier-frame 131. To this ring gear 90 is attached the cam box 92 of the cam system II. In the cam box 92 is a slide 91, positioned radially displaceable to the cylinder. The cam parts 97 and 98, which actuate the needle butts 3", are attached to slide 91 and may thus be brought, by a connecting ring 31', into engagement and out of engagement with the needle butts 3". The lower connecting ring 36' has at its upper face corresponding sloping surfaces 369' which, in the twisting of the upper connecting ring 31', engaging at its shoulder 311', support themselves by an angle on the slanting surfaces 310' of the connecting ring 31' and thus displace upward the connecting ring 31' axially to the cylinder. On this connecting ring 31' drags the bolt 94 revolving with the cam system II, which is attached at a bell crank 93. Through the axial displacement of the connecting ring 31' the bolt 94 is pressed up, and the bell crank 93, pivoted on the cam box 92 by bolt 96, acts upon the pin 95 attached on the slide 91. The slide 91 is pressed thus outward and cam system II switched off.

The actuation of the cam system II takes place during the knitting of the reinforced part of the hose, revolving with the triple cylinder-rotation-speed at each third revolution, in order to knit back the reinforcement thread alone from the end margin of the reinforcement to the starting margin.

The periodic operation of the connecting ring 31' and the accompanying switching-on and switching-off of the cam system II takes place through conventional control means for example, through a revolving cam-disc, acting upon transmission bars, to engage at the shoulder 311' of the connecting ring 31'. In the position shown in FIG. 15 of the connecting ring 31' the cam system II is switched-on.

In a similar manner is operated the coupling for the picking up of the thread-guide S for the reinforcement thread (FIGS. 14 and 21). This coupling consists of a clutch 28 with a lining 27 and is connected by means of several sockets 29 with the gear 110. In each carrier socket 29 is a coil spring 291 directed at the clutch plate 28, presses on the plunger 292 and thus presses the covering 27, with the clutch switched-on, flexibly against the thread guide carrier ring 25. The connecting of the clutch takes place through cam plates 31 and 30, in which the connecting ring 30 is stationarily mounted at the guide cylinder 111', while the connecting ring 31 is rotatable through a specific angle and axially displaceable by the slanting surfaces 300 and 310 facing one another. The guide cylinder 111' is supported by a carrier-ring 131' on the machine frame 132. The reinforcement thread guide S is attached at a carrier-arm 20', screwed-fast on a block 24 on thread-guide-carrier-ring 25. By means of the ball bearing 113 the thread-guide-bearer-ring 25 is rotatable on the stationary guide-ring 112, attached to the guide-cylinder 111' and is guided by angle-pieces 26. A buffer 23 takes the impact at the stopping of the reinforcement-thread-guide S through the buffer 21 (FIG. 10) beside the thread-guide for the base-thread G, as shown in FIG. 7a, when the reinforcement-thread is knitted together with the base-thread by the stationary cam system I.

By the pair of gears 11 and 110 the clutch plate 28 is rotated constantly at the same speed as the cam system II. Through the connecting bars 32 engaging at the shoulder 311 connecting ring 31 is turned through a specific angle and the clutch 27, 28 is pressed against the thread guide carrier ring 25 for the actuation of the re-

inforcement thread guide S'. The engagement of clutch 27, 28 takes place each time shortly before or during the release of the thread guide S' through withdrawal of the buffer 21 (FIG. 10), for the knitting back of the reinforcement thread, thus at each third revolution of the cam system II for the reinforcement-thread. The throwing out of the clutch takes place at or shortly after the buffer 23 has bounced against the stop 21 (FIG. 10), as already described in the previous embodiment of the invention, thus again the thread-guide for the reinforcement thread S (FIG. 7a) returns to the starting point near the base thread G' after a revolution. While the cam system II revolves twice disengaged, the thread guide S for the reinforcement thread rests beside the thread guide for the base-thread G and the clutch 27, 28 is released. This release of the clutch avoids a needless sliding of the reinforcement-thread-guide S further rotation of flange ring 111 (FIG. 10), so that wear and tear is avoided and power to overcome friction is saved.

Together with the revolving cam system II is also periodically switched-off and -on the rotating sinker cam 16, so that sinkers are not simultaneously operated by the sinker cam 16 rotating with the cam system II and the stationary sinker cam 17. For the control of the sinker cam 16 is mounted on the upper carrier frame 132 a stationary ring 165 (FIG. 14), on which a guide-pin 162 of the sinker cam slide 161 slides (FIGS. 16, 17, 18 and 19). A spring 161' (FIG. 19) presses the slide 161 radially inward, which is positioned radially displaceable on the gear 100 under the cover ring 101 and rotates with it. The slide 161 has attached on the sinker cam 16.

In the sector, in which the stationary sinker cam 17 is positioned are attached at the ring 165 two steering latches 163 and 164 which are pivotable on the bolts 163' and 164', which according to their position close or open the orbit of ring 165. If the sinker cam 16 is switched-off, then the guide pin 162 runs along the inside of the ring 165, with the switched-on sinker cam 16, however, it runs along the outside of the ring 165. FIG. 16 shows the position at the moment of the switching-off of the sinker cam 16, after over the sector $\overline{AB}$ the reinforcement thread has just been knitted back alone from B to A. The sinker cam 16 has overtaken the sinkers 14 revolving with the cylinder and operated them by the sinker butts 14''. The guide pin 162 slides along at the steering latch 163 swung inward, whereby the spring 161' presses inward the slide 161. During the next two revolutions the sinker cam 16 remains switched-off, so that in the meeting of the revolving sinker cam 16 with the stationary sinker cam 17 the sinker butts 14'' run by, uninfluenced behind the sinker cam 16 and only the sinker cam 17 is in operation (FIG. 17). At each revolution of the cam system II the cylinder Z turns together with the sinker-ring 141 by 120° .

FIG. 18 shows the position of the sector $\overline{AB}$, in which the reinforcement is knitted, after a further revolution of the sinker cam 16 precisely in the position in which the guide pin 162 slides along the inwardly swung steering latch 164 to the outside of the ring 165, by which the sinker cam 16 is switched-on and upon overtaking of the sinkers 14 engages the sinker butts 14'', while the reinforcement-thread alone is knitted back from B to A.

FIG. 19 shows the same position in perspective view, as already described.

The movements of the steering latches 163 and 164 take place independently of each other through two cam-discs 191 and 192 (FIG. 20), which revolve jointly with the shaft 19, however are arranged out of phase by 120° . The shaft 19 makes one revolution per cylinder-rotation and is driven by the main shaft of the machine. The movement of the cam following bell cranks 193 and 194 is transmitted by levers 169 and 168, and links 167 and 166 to the steering latches 163 and 164 respectively. Since the cam shaft 19 revolves continuously, also during

the knitting of the unreinforced parts, in which the sinker cam 16 must remain switched-off, the tilting levers 183 and 184, rotatably mounted by shaft 187, will act from the switch-drum 18 by the control cams 181 and 182; the bell cranks 193 and 194 are held in revolved position, so that the cams 191 and 192 remain without influence. The two tilting levers 183 and 184 are in each case, by connecting rods 185 and 186, coupled to levers 169 and 168 respectively, in order to cut out the switch-movement of the drum 18 on the switch-movement of the cam discs 191 and 192.

Of course, this steering device may also be used for a multiple, for example four-fold or five-fold rotation speed of the cam system II. Only the steering times of the cams (lugs) 191 and 192 are changed. In practice, however, a three-fold rotation speed ($v_{II}=3v_z$) has proved advantageous and sufficient.

In the mode of operation of the needles 2, together with the pattern butts 4 and the pattern devices M_1 and M_2 , there is nothing changed of the first described embodiment, in which the cam system II revolves only with double the cylinder speed ($v_{II}=2v_z$), since this runs synchronously with the cylinder rotation. This manner of operation has already been described in detail on the basis of FIGS. 7a, 7b and 7 and applies likewise for this part of the invention.

In the two described embodiments of the invention the reinforcement-thread-guide S rotates periodically with the cam system II, when the reinforcement-thread alone is knitted back from the end-margin of the reinforcement.

In FIG. 22 is shown the device required therefor to feed the reinforcement thread S_F to be unwound from a spool S_F to the revolving reinforcement thread guide S. The spool S_F , on which the reinforcement thread S_F is wound up, is set up on a spool-holder 126 which is attached at the gear 120. Likewise is attached at the gear 120 a thread-brake, for example a known plate-brake 127 with an adjustable spring 127', as well as thread-loops 128', 128'' and 128'''. The thread-stretcher 128 is seated horizontally pivotable on a bolt 129, which is attached at the gear 120. A tension spring 129' effects a swinging movement of the thread-stretcher 128 against the thread-pull of the thread S_F sliding through the loops 128' and 128''. This swinging movement compensates in known manner non-uniform thread-pull, and the stretcher 128 takes up the temporarily surplus thread into a loop between the thread-loops 128' and 128''.

The gear 120 is turnably seated by means of an adjusting collar 136' on a stationary tube 136 and is driven by the gear 12, attached on the shaft 8 and revolving with it.

The shaft 8 is turnably seated at its upper end in the carrier plate 135, while the tube 136 is rigidly connected with the carrier plate 135. The tube 136 serves to hold the stationary dial cap 137 as well as to seat the drive shaft 122 for the dial disc 125, which always revolves synchronously with the cylinder. The drive of the dial disc 125 takes place by the gears 123 and 124 by a shaft 8' in known manner and is here not described in detail. The drive of the gear 120 and therewith of the spool S_F revolving around the pipe 136, takes place separately from the dial disc drive by the shaft 8, since the dial disc must be continuously driven, while the spool S_F revolves only during the knitting of the reinforced hose parts. During the further knitting process the shaft 8 is stopped by the clutch 80, as already described.

Since the reinforcement thread guide S periodically revolves with the cam system II during the knitting-back of the reinforcement thread alone, the spool S_F must in each case revolve likewise, so that the thread S_F is not wound around the tube 136. During the knitting of the course formed jointly by the base and reinforcement thread, the reinforcement thread guide S remains behind, as already described, at the stationary cam system I and

is overtaken by the continuously revolving cylinder Z, i.e., up to the end margin of the reinforcement, the reinforcement thread guide S is carried along with the cam system II. If the cam system II revolves with double the cylinder-speed, then the reinforcement thread guide S is taken along during one revolution of the cam system II and during the second revolution at the buffer 21 (FIG. 10) held back. If the cam system II revolves with the triple cylinder speed, then the reinforcement thread guide S is carried likewise during one revolution of the cam system II, but is held back during the second and third revolution at the buffer 21. From this it is evident that, independent of the speed of revolution of the cam system II, in both cases the reinforcement-thread-guide S revolves only once during each cylinder-rotation, even though with different speed, namely in the first case with $2v_z$ and in the second case with $3v_z$.

The spool S_p therefore needs only carry out in each case one revolution per cylinder rotation and, therefore, is continuously driven with cylinder-rotation-speed, while the reinforcement-thread-guide S revolves intermittently once per cylinder rotation with the respective speed of the cam system II. The transmission of the gears 12 and 120 is consequently the same as between the gears 7 and 6' according to FIG. 14 or FIG. 6.

In order to compensate the variable distance from the spool S_p to the reinforcement-thread-guide S at continuous thread-supply, occasioned by the continuous revolution of the spool S_p and the intermittent revolution of the reinforcement-thread-guide S, is the task of the thread-stretch-device 128, 127, 129', which is described above with reference to FIG. 22. During the knitting of the unreinforced hose parts the revolution of the spool S_p is stopped through the coupling 80 simultaneously with the other revolving parts.

What is claimed is:

1. A process for the circular knitting of partially reinforced hosiery, such as hose having at least one of a reinforced heel, toe, sole, and the like, by means of an endless reinforcement thread in addition to a base thread which comprises jointly knitting the base thread for the hosiery and the endless reinforcement thread along the desired reinforcement portion of one course from the starting edge of said reinforcement portion, continuing the knitting of the base thread alone from the terminal edge of said reinforcement portion in forward direction around to the starting edge of said reinforcement portion to complete the course, while knitting the endless reinforcement thread alone in a next intermediate reinforcement thread course in reverse direction back to the starting edge of said reinforcement portion, and repeating the cycle, whereby hosiery is knitted having a reinforced portion alternately containing a course of jointly knitted base and reinforcement threads and an intermediate course of separately knitted reinforcement thread.

2. A process according to claim 1 wherein during each knitting cycle, the knitting in reverse direction of the reinforcement thread alone is carried out at such a rate with respect to the knitting of the base thread above in forward direction that the same reaches the starting edge of the reinforcement portion at the same time that the base thread reaches the starting edge from the opposite direction.

3. A process according to claim 1 wherein a knitting machine is used for continuously automatically carrying out the knitting having a stationary cylinder and separate oppositely revolving cylinder needle cam systems for the knitting in forward direction and reverse direction, traveling at equal and constant speed.

4. A process according to claim 1 wherein a knitting machine is used for continuously automatically carrying out the knitting having a rotating cylinder and a stationary needle cam system for the knitting in forward direction and a moving needle cam system for the knitting in

reverse direction traveling at least at twice the speed of rotation as the cylinder and in the same direction of rotation as the cylinder.

5. An apparatus for the circular knitting of partially reinforced hosiery, such as hose having at least one of a reinforced heel, toe, sole, and the like, by means of an endless reinforcement thread in addition to a base thread which comprises means defining a knitting cylinder having a plurality of knitting needles disposed thereon moveable in axial direction, said needles having elongated shank portions carrying butts thereon to form butt-rows axially displaced with respect to one another, and a main base thread needle cam-means and a secondary reinforcement thread needle cam means disposed adjacent said cylinder and axially displaced with respect to one another, said cylinder and both said cam means being positioned for relative peripheral movement with respect to each other about the axis of said cylinder, one of said main cam means being rotatable with respect to the other, each said cam means being capable of operatively engaging butt means of a corresponding butt row to actuate said needles for knitting the base thread and reinforcement thread to form the partially reinforced hosiery.

6. An apparatus according to claim 5 wherein said cylinder is stationary and both said cam means are adapted to revolve around said cylinder in opposite directions at substantially the same speed.

7. An apparatus according to claim 6 wherein each of said cam means is mounted for independent movement on a ring coaxially positioned with respect to said cylinder.

8. An apparatus according to claim 5 wherein one of said cam means is stationary, said cylinder is rotatable and the other of said cam means is adapted to revolve around said cylinder at substantially two times the speed of rotation of said cylinder.

9. An apparatus according to claim 8 wherein said revolving cam means is mounted for independent movement on a ring coaxially positioned with respect to said cylinder.

10. An apparatus according to claim 5 wherein a thread guide is provided for the reinforcement thread, mounted as a trailing thread guide slidable on a guide ring.

11. An apparatus according to claim 5 wherein each needle has at least one butt means and a portion of said needles have an additional butt means whereby a continuous butt row and one partial butt row are formed around the cylinder outer surface axially displaced with respect to one another and correspondingly positioned for engagement by said cam means respectively.

12. An apparatus according to claim 5 wherein selector means for the selection of needles to be actuated for knitting the reinforcement portion of the hosiery.

13. An apparatus according to claim 12 wherein for the selection of needles to be actuated for knitting the reinforcement thread together with the base thread by said main cam means and for knitting the reinforcement thread alone by said secondary cam means, selector means are provided, one of said selector means being arranged relatively immediately before and another of said selector means being arranged relatively immediately after the main cam means.

14. A process for knitting a tubular article with partial reinforcements which includes continuously knitting a base thread in one circular direction, knitting a reinforcing thread with the base thread simultaneously and identically for less than a complete circular turn, reversing the direction of knitting of the reinforcing thread alone for at least part of such incomplete turn to form a course of only said reinforcement thread and again reversing the knitting direction of the reinforcing thread and knitting it and the base thread to form a further reinforced course of an incomplete turn.

15. An apparatus according to claim 5 wherein one of said cam means is stationary, said cylinder is rotatable

and means is provided to rotate the other cam means periodically during the cylinder rotation and in the same direction thereof at a speed a multiple of the cylinder speed.

16. An apparatus according to claim 15 in which is provided a guide for the reinforcing thread and coupling means to rotate the reinforcing thread guide in unison with the periodically rotatable cam means.

17. An apparatus according to claim 16 in which said coupling means includes an upper connecting ring having a lower cam surface, a round connecting ring supporting the first said connecting ring and provided with an upper cam surface, both side rings being coaxial with the cylinder and rotatable with respect to each other to actuate said coupling.

18. Apparatus as set forth in claim 5 in which are provided sinkers cooperative said needles to knit the reinforcement thread, a cam for actuating said sinkers, and a stationary guide ring coaxial with said cylinder to control said sinker cam.

19. Apparatus as set forth in claim 18 in which said guide ring is provided with a pair of gates swingable radially in and out independently of each other and control said sinker cam.

20. Apparatus as set forth in claim 5 in which is provided a spool for containing the reinforcement thread

and means for supporting said spool and rotating said spool about the axis of said cylinder in unison with said cylinder.

21. Apparatus as set forth in claim 5 in which is provided a reinforcement thread guide, means to rotate the thread guide about the cylinder axis in unison with the cam for actuating said needles for such reverse knitting during a portion of its rotation in the forward direction.

22. Apparatus as set forth in claim 21 in which is provided take-up means for the reinforcement thread slack between said guide and spool for the reinforcement thread.

UNITED STATES PATENT OFFICE
CERTIFICATE OF CORRECTION

Patent No. 3,192,741

July 6, 1965

Ewald Hänel

It is hereby certified that error appears in the above numbered patent requiring correction and that the said Letters Patent should read as corrected below.

Column 4, line 31, for "or also" read -- (or also --; column 5, line 42, for "pseed" read -- speed --; column 8, line 1, for "S" read -- S' --; column 15, line 18, for "needs" read -- need --; column 16, line 18, after "said", second occurrence, insert -- cylinder and said --; line 51, after "means" insert -- is provided --.

Signed and sealed this 5th day of April 1966.
